(57) **CLAIM**

The ornamental design for a rear combination lamp for automobile as shown and described.

DESCRIPTION

FIG. 1 is a front and left perspective view of a rear combination lamp for automobile, showing our new design; FIG. 2 is a front elevation view thereof; FIG. 3 is a top plan view thereof; FIG. 4 is a bottom plan view thereof; FIG. 5 is a left side elevation view thereof; FIG. 6 is a reference perspective view thereof; FIG. 7 is a reference perspective view thereof; FIG. 8 is a reference rear elevation view thereof; FIG. 9 is a reference right side elevation view thereof; and, FIG. 10 is a reference perspective view thereof.

The claimed design is indicated by the relatively dark portions in the figures, while the relatively light and deemphasized portions are environmental and form no part of the claimed design.

1 Claim, 10 Drawing Sheets
